UNITED STATES PATENT OFFICE.

JAMES DAWSON, OF WALTHAM, MASSACHUSETTS.

JACK-ADJUSTER.

SPECIFICATION forming part of Letters Patent No. 683,681, dated October 1, 1901.

Application filed April 27, 1901. Serial No. 57,717. (No model.)

To all whom it may concern:

Be it known that I, JAMES DAWSON, a citizen of the United States, residing at Waltham, in the county of Middlesex and State 5 of Massachusetts, have invented certain new and useful Improvements in Jack-Adjusters; and I do hereby declare the following to be a full, clear, and exact description of the invention, such as will enable others skilled in the 10 art to which it appertains to make and use the same.

This invention relates to devices for adjusting the connection between the harness-treadle and the jack in a loom; and it consists of a metallic adjusting device constructed as hereinafter fully described and claimed.

In the drawings, Figure 1 is a side view of the jack-adjuster. Fig. 2 is a plan view of the same.

20 A is a flat bar of metal provided with a hook B at one end for engaging with the jack. C represents inclined projections at the other end of the bar, arranged on the same side of it as the hook B and projecting toward the

said hook. The treadle is placed in engagement with either of the projections C, according to the adjustment required.

This metallic adjuster is intended to take the place of the leather strap or "jack-strap" now commonly used to connect the harness-treadle with the jack.

What I claim is—

An adjusting device for a loom-harness formed of a single piece of metal and comprising a flat bar A of greater width than 35 depth, a hook at one end thereof which is bent over the said bar A, and a series of projections C at the other end thereof projecting above the upper surface of the said bar and inclined toward the said hook, substantially 40 as set forth.

In testimony whereof I affix my signature in presence of two witnesses.

JAMES DAWSON.

Witnesses:

ALICE J. MURRAY,
FREDERICK K. DAGGETT.
